DESIGN FOR A TRUSS ROD UNIT

Harry H. Henry, Chicago, Ill., assignor to Battery
Patents Corporation, Chicago, Ill., a corpora-
tion of Illinois

Application November 2, 1936, Serial No. 65,655

Term of patent 14 years

To all whom it may concern:

Be it known that I, Harry H. Henry, a citizen
of the United States, residing at Chicago, county
of Cook, and State of Illinois, have invented a new,
original, and ornamental Design for Truss Rod
Unit, of which the following is a specification,
reference being had to the accompanying draw-
ing, forming a part thereof, in which:

Figure 1 is a side elevational view of truss
rod unit, showing my new design; and Fig. 2, a
front elevational view.

I claim:

The ornamental design for a truss rod unit,
as shown.

HARRY H. HENRY.
